UNITED STATES PATENT OFFICE

RICHARD GEARTNER, OF MOULTON, TEXAS

AUTOMATIC ACCORDION

Application filed May 18, 1931. Serial No. 538,104.

This invention relates generally to automatic or self playing musical instruments and more particularly to an automatic accordion.

The main object of the invention is to provide a mechanism whereby an accordion or similar wind operated instrument may be automatically played and the various keys thereof depressed in proper sequence and combinations under the control of the note determining perforations in a conventional form of music roll or scroll.

Another object is to provide a mechanism of this kind which includes a means for supplying compressed air to the accordion so that its bellows need not be expanded and contracted and so that its ends may remain stationary whereby operating mechanisms mounted adjacent the ends of the accordion may be used for operating the keys thereof.

Still another object is to provide in combination with an accordion or like wind instrument having banks of movable keys, suitable frames mounted adjacent the key boards, pivot shafts or rods extended thru the frame in spaced relation, levers pivoted in spaced relation upon the rods with one end of the levers having a bearing upon the keys, and electro-magnetic means for operating said levers.

Another object is to provide a device of the above character in a novel, efficient and relatively simple form.

With these and other objects in view the invention resides in the novel construction and arrangement of parts as hereinafter set forth and claimed, reference being had to the accompanying drawings wherein is illustrated by way of exemplification a preferred embodiment of the invention and wherein:

Figure 1 is a front view of the instrument as a whole, showing the accordion, the operating mechanism, the paper music roll and compressor for supplying air to the accordion.

Figure 2 is an enlarged section along the line 2-2 in Figure 1.

Figure 3 is an enlarged section along the line 3-3 in Figure 1.

Figure 4 is an enlarged front elevation of the melody key board of the accordion and a part of the operating mechanism for the keys thereof.

Figure 5 is a detail side view of a portion of the operating electromagnets.

Figure 6 is a detail in perspective of the method of mounting the key operating levers on their supporting pivot shafts.

Figure 7 is a sectional detail view showing the form of music roll or scroll assembly used in controlling the operation of the key operating mechanism.

Figure 8 is a diagrammatic wiring plan of the operating mechanism for one key of the accordion.

Referring now with more particularity to the drawings and as shown in Figure 1 thereof of a case or housing 1 is provided the same being preferably, though of course not necessarily divided into three compartments or sections 2, 3 and 4 set apart by horizontal shelves 5 and 6. The numeral 7 designates a conventional two octave accordion having the piano type melody key board 8 and the button type bass and chord key board 9, the former having the usual white keys 10 and black keys 11 and the latter the usual push button keys 12. The accordion 7 is mounted horizontally and centrally in the case 1 on the upper shelf 5 on stands or brackets 13 secured to the said shelf 5. The bellows 14 of the accordion are compressed and held rigidly in that position by a tie strip 15 secured to the ends of the instrument at the upper side and which cooperates with the brackets 13. An electrically driven air compressor 16 of conventional form is suitably mounted in the case 1 as for instance in the lower compartment 4 thereof and the output thereof is conducted to the interior of the accordion 7 through a tube 17 connected to an elbow 18 on the said accordion. Air under pressure is thus provided in the accordion to operate the reeds thereof when the keys are pressed without necessitating the usual expansion and contraction of the bellows 14. The ends of the accordion thus

remain stationary allowing the use of oper- 100

ating mechanisms mounted at its ends on the shelf 5 for operating or pressing the keys.

The operating mechanism or assembly for the melody key board 8 will be first described.

- 5 This key board in the accordion here shown contains fifteen white or natural keys and ten black or sharp and flat keys making a total of twenty-five operating levers and elements necessary. A lower plate 19 is secured by screws 19a to the shelf 5 beside the end of the accordion 7 and two spaced pivot shafts or rods 20 and 21 are vertically secured in this plate by nuts 22 and extend alongside and adjacent the edge of the key board 8 as shown.
- 10 An upper plate 23 is provided and the upper ends of the shafts 20 and 21 are secured thereto by nuts 24. One pivot shaft as for instance 20 is disposed somewhat rearwardly of the other shaft 21, and the former carries the arms or levers 25 for operating the white or natural keys 10 while the latter carries the arms or levers 26 for operating the black or sharp and flat keys 11 of the key board 8. The levers 25 and 26 are formed of two sections 27 and 28 joined together at their ends to carriers or pivot blocks 29 rotatably mounted on the shafts 20 and 21. The carriers 29 have bores 30 for receiving the shafts 20 and 21 and have channels 31 in their upper faces in which the ends of the lever sections 27 and 28 are disposed. Screws 32 are passed through the inner ends of the lever sections 27 and 28 and are threaded in the carriers 29 whereby the said sections are held rigidly in the channels 31. The carriers 29 with their levers 25 and 26 are mounted on the shafts 20 and 21 one above the other as shown and a collar 33 is mounted beneath each carrier, the collars being provided with set screws 34 whereby they may be secured in any desired position upon the shafts to support the various levers at the proper height and in the proper spacing so that the ends thereof will rest adjacent the keys on the key board 8
- 15 which they are to operate. This arrangement is clearly shown in Figure 4. The ends of the levers 25 and 26 adjacent the keys 10 and 11 are twisted axially through an arc of ninety degrees and are angularly bent as shown at 56 in Figure 3 to rest in substantially parallel relationship with the keys when in their inoperative position and these ends of the levers have felt striking pads 35 to contact the keys in the operation of the levers. The purpose 20 of these pads 35 will be obvious. The opposite ends of the levers 25 and 26 have apertures 36 for a purpose to be described. A plurality of electromagnetic operating elements 37 for the levers 25 and 26 are provided, one for each 25 lever, and each operating element comprises an electromagnet 38 secured to one leg 39 of an L-shaped bracket 40, the other leg 41 of which extends alongside and parallel to the electromagnet. An arm 42 is pivoted intermediate its ends to the end of the leg 41 of

the bracket 40 at 43, the inner end of the said arm 42 being disposed adjacent the end of the electromagnet 38 and adapted to be drawn towards that end when the electromagnet is energized thus swinging the arm on its pivot 70 43. When the end of the arm 42 is swung inward to the end of the electromagnet 38 as described its other or outer end comes in contact with a rubber bumper 44 carried by the member 45 secured to the bracket leg 41, this bumper limiting the said swinging movement of the arm and preventing the noise which otherwise would occur if the arm struck the end of the electromagnet. The operating elements 37 thus formed are secured in spaced 75 relationship by the legs 39 of the brackets 40 to two angle irons 46 and 47 secured vertically between the upper and lower plates 19 and 23 of the melody key operating mechanism. The angle iron 46 carries the electromagnets for 80 operating the levers 25 and the other angle iron 47 carries the electromagnets for operating the levers 26, the said angle iron 46 being mounted adjacent the outer edges of the plates 19 and 23 and towards the rear of the same 85 while the angle iron 47 is mounted adjacent the front and inner corner of the said plates. The electromagnets on the two angle irons are oppositely disposed, that is, the free or outer ends 48 of the arms 42 are extended 90 towards each other and so are disposed substantially in forward alignment with the outer ends of the levers 25 and 26 to which they are connected. Connecting rods or links 95 49 are loosely looped through the apertures 36 and around the outer ends of the levers 25 and 26 and extend forwardly therefrom, and are passed loosely through apertures 50 provided in the outer ends of the arms 42 operated by the electromagnets 38. Small wooden blocks 51 are disposed on the rods 49 at each side of the ends of the arms 42 and are held loosely in engagement therewith by nuts 52 threaded on the rods as shown. It will thus 100 be apparent that when the electromagnets 38 are energized and the arms 42 are operated thereby as described, the swinging movement of the outer ends 48 of the said arms will be transmitted through the connecting rods 49 to the levers 25 and 26 causing the same to swing on the pivot rods 20 and 21 and causing their inner ends to engage and depress the keys 10 and 11. When the energization of the electromagnets 38 is cut off the keys 10 and 11 will in the usual manner return to their normal position and the levers 25 and 26 and arms 42 will likewise return to normal position. In their normal position the ends 105 of the arms 42 adjacent the electromagnets 38 rest against vertically set bumper rods 53 secured at their ends by nuts 54 to the upper and lower plates 19 and 23 and covered with rubber tubing 55 as shown. The levers 42 are thus prevented from rattling by coming in contact with the bumpers 44 and the rubber 110 115 120 125 130

covered bumper rods 53 at each end of their stroke. The movement or "throw" of the levers 25 and 26 and the arms 42 is of course such that the keys are depressed to the full or normal extent and no more. The apparatus as mounted between the upper and lower plates 19 and 23 forms a unit for operating the keys of the melody key board 8 and the unit may be readily removed from the shelf 5 when necessary by removing the screws 19a holding the lower plate 19 in place.

The bass key operating mechanism is similar to the melody key operating mechanism and is located adjacent the opposite end of the accordion. A lower plate 58 is secured by screws 59 to the shelf 5 adjacent the end of the accordion and three pivot shafts 60, 61 and 62 are secured vertically to the lower plate by nuts 63, the said pivot shafts being spaced apart laterally and disposed one behind the other. An upper plate 71 is provided and the pivot shafts are secured thereto by nuts 72. Each pivot shaft carries eight operating levers to operate the eight bass keys 12 in each of the three rows as shown, the levers 64 on the forward shaft 60 operating the keys on the first or inner row, the levers 65 on the next shaft 61 operating the keys on the second or middle row and the levers 66 on the rear shaft 62 operating the keys on the third or outer row as best seen in Figure 2. Like the aforesaid operating levers 25 and 26 these operating levers 64, 65 and 66 are formed in two sections connected to carriers or pivot blocks 29 rotatably mounted on the pivot shafts 60, 61 and 62 and held in proper spaced relationship thereon by adjustable collars 33 so that the ends of the levers will rest over the keys they are to operate. The end portions of the levers 64, 65 and 66 are twisted axially through an arc of ninety degrees as indicated at 67, the end portions of the levers 64 adjacent the accordion 7 being also bent arcuately rearward and having their extreme ends 68 turned sharply outward to lie in substantially alignment with and proximity to the ends of the keys 12. Similarly the levers 64 are bent arcuately rearward and have their extreme ends 69 bent inward to rest in like manner adjacent the ends of the second row of keys 12. The levers 66 are bent angularly outward and extend over the ends of the last or outer row of keys. Felt pads 70 are provided on the ends of all of the levers to contact the keys 12. Three sets of eight electro-magnetic operating elements 37 similar to those used in the melody key operating mechanism are provided, the same being mounted on angle irons 46 secured vertically between the upper and lower plates 71 and 58 and arranged one behind and inwardly of the other as shown, the elements 37 on the outermost and front angle iron operating the forward levers 64, those on the next angle iron operating the levers 65 and those on the rear and inner angle iron operating the levers 66. To facilitate their connection to these operating elements 37 the forward levers 64 extend outwardly beyond the ends of the next levers 65 and the ends of these levers 65 extend outwardly beyond the ends of the rear levers 66. Connecting rods or links 49 connect these ends of the levers 64, 65 and 67 with the ends of the arms 42 of the electromagnetic operating elements 37, the said connecting rods passing loosely at their ends through the ends of the levers and arms and having wooden blocks 51 at each side held in place by nuts 52 in the manner hereinbefore described. The energization of the electromagnets 38 will thus swing the operating levers 64, 65 and 66 on the pivot shafts 60, 61 and 62 and cause the ends of the levers to press upon and operate the keys 12. The keys 12 will return to their normal position when the current through the electromagnets 38 is cut off and the operating levers and arms 42 will return to their normal position. Bumper rods 53 covered by rubber tubing 55 are provided to engage the arms 42 when they are in their normal position. Like the operating mechanism for the melody key board this operating mechanism for the bass key board forms a unit which may be readily removed by removing the screws 59.

In order to energize the various electromagnets 38 in the proper sequence and in the proper combinations to press the desired keys of the accordion and play a composition of music a conventional music roll or scroll A is utilized, the same being wound on the spools B mounted in the stand C on the shelf 6. The motor D operates the spools C. The paper A passes behind the contact roller E and a plurality of small brushes F are arranged behind this roller and are adapted to contact the same through the perforations G in the paper as the same is rolled from one spool to the other by the motor D. The brushes F only make contact with the contact roller E during the time the perforations G are in registry with the brushes as will be understood, the spacing and position of the perforations thus determining the number and sequence of operations of the brushes. The foregoing structure is conventional in form and no invention therefor is herein claimed.

Referring to Figure 8 the wiring arrangement of one electromagnet 38 is shown. One terminal of the winding of the electromagnet is grounded at 74 to any suitable part of the frame supporting the electromagnets and the other terminal is connected by a wire 75 to one of the brushes F. The source of electrical current for energizing the electromagnets is shown as being a conventional form of rotary converter H for converting alternating current to direct current and one terminal thereof is connected by a wire 76 to the

contact roller E while the other terminal is grounded at 77. Thus it will be seen that as the brush F contacts the roller E through a perforation in the roll A the output of the converter H will be connected through the brush and roller to the electromagnet 38 energizing the same and causing the lever 64 to press the key 12. The operation and wiring of the other electromagnets 38 are exactly the same, each electromagnet being connected to a separate brush F by a wire 75. The perforations G in the music roll A being then properly disposed and cut the electromagnets 38 will be energized in proper sequence and combination to press the various keys of the accordion so that it will play the desired composition. It is obvious that any other suitable source of direct current other than the converter H may be used as desired and it will be also obvious that the form of music roll in which streams of compressed air flow through the perforations and operate switches to make the electrical contacts may be used in lieu of the brush and contact roller form here shown. To facilitate the wiring of the electromagnets 38 insulating connecting or binding post strips 78 are secured by screws 79 and spacers 80 to the angle irons 46 supporting said electromagnets. The ungrounded terminals of the electromagnets are connected to screws 81 in these strips 78 and the wires 75 connecting the electromagnets and the brushes F are then connected to these screws and cabled together as shown at 82 in Figure 5.

The operation of the invention will be apparent from the foregoing description. Any desired or suitable form of starting and stopping switch (not shown) may of course be used to control the compressor 16, motor D and converter H or the same may be controlled by the insertion of a coin in a coin controlled switch in conventional manner. As herein before pointed out the use of the air compressor 16 whereby the ends of the accordion may remain stationary makes possible the use of the operating mechanisms secured adjacent the ends to operate the key thereon so that an efficient and durable arrangement is provided.

While I have herein set forth a certain manner and method of construction and arrangement of the parts of my invention it is understood that I may vary from the same in minor structural details so as best to construct a practical device for the purposes intended, not departing from the spirit of the invention and within the scope of the appended claims.

I claim:

1. In a musical instrument, an accordion having keys at its ends, means for supplying compressed air to the interior of the accordion to operate the reeds thereof without expansion and contraction of the accordion, a plu-

rality of pivoted levers mounted adjacent the ends of the accordion and adapted to engage the keys thereof, and means for operating said levers to press the keys of the accordion.

2. In a musical instrument, an accordion having keys at its ends, an air compressor for supplying compressed air to the accordion, the ends thereof remaining stationary, a plurality of pivoted levers arranged at the ends of the accordion to engage the keys thereof, electromagnetically operated means for operating said levers to press the accordion keys, and means for selectively energizing the said lever operating means.

3. In a musical instrument, in combination with a perforated music roll, an accordion having keys at its ends, means for supplying compressed air to the accordion, the ends thereof remaining stationary, a plurality of operating levers arranged adjacent the ends of the accordion to engage the keys thereof, and electromagnetic operating means for operating the said levers to press the keys of the accordion under the control of the perforated music roll.

4. In a musical instrument, in combination with a source of current and perforated scroll, a contact roller on one side of the scroll and brushes on the other side adapted to contact said contact roller through the perforations in the scroll, an accordion, an air compressor connected to the interior of the accordion, operating mechanisms arranged adjacent the ends of the accordion, the said operating mechanisms comprising a plurality of pivoted levers adapted to engage the keys of the accordion, electromagnets, arms pivoted to the electromagnets for swinging movement thereon and under the control thereof, rods connecting the said levers and the arms on the electromagnets, the said electromagnets being connected to the source of current through the said brushes and contact roller.

In testimony whereof I affix my signature.

RICHARD GEARTNER.
